UNITED STATES PATENT OFFICE.

ALEXANDER B. ALLAN, OF GLASGOW, SCOTLAND.

WIRE ROPE.

No. 861,230.

Specification of Letters Patent.

Patented July 23, 1907.

Application filed February 26, 1906. Serial No. 303,113.

To all whom it may concern:

Be it known that I, ALEXANDER BRANDER ALLAN, wire-rope manufacturer, a subject of the King of Great Britain and Ireland, and a resident of Rutherglen, 5 Glasgow, Scotland, have invented certain new and useful Improvements in Wire Ropes, of which the following is a specification, and for which a patent has been applied for in Great Britain, No. 13,057, dated the 24th June, 1905.

10 This invention has reference to an improved method of manufacturing wire ropes for haulage, hoisting and other purposes and to the tapered wire rope or product so produced; and essentially consists in dropping or removing one or more wires from the outside layer of 15 each strand, and changing the diameter of the inside or core wires, or reducing their number at the various steps or reductions, so as to produce a tapered wire rope.

The main feature of my improvements is an alteration in the circumference or diameter of the rope by reducing or increasing the number of wire filaments in each strand and so varying the size of the ropes made in this way in any length or size in the ordinary construction with the wires laid in one direction and the strands in the other direction, in construction usually termed 25 "Langs" or "Albert lay" with the wires and strands laid in the same direction right or left, or in the make of rope called "flattened strand" either in "Langs" or ordinary construction. Wire ropes made in this way can have any number of strands from 3 to 9 and from 30 5 to 91 wires per strand. And in order that my said invention and the manner of carrying same into practice may be properly understood I have hereunto appended a sheet of explanatory diagrammatic drawings of transverse sections of wire ropes each with six strands of 35 wire, in which

Figure 1 represents four inner wires as covered with ten outer wires. Fig. 2 illustrates the strands as having three inner wires as covered with nine outer wires, both the outer and inner wires of the strands shown in Fig. 1 40 having each a wire removed to reduce the diameter and produce a taper on the complete rope. Fig. 3 illustrates the strands as having seven inner wires and eleven outer wires, and Fig. 4 illustrates same with seven inner wires and ten outer wires, the outer wires being one less than 45 in Fig. 3, and the inner wires the same as in Fig. 3 but reduced in diameter to give the tapered formation to rope. Fig. 5 is a plan view of the rope showing its tapering form, with cross sections at several points to show the diminishing number of strands.

50 Referring to these drawings:—the novel feature of the invention is to make a rope tapering from one size to another, keeping the outside wires *a* of strands always

the same size to avoid welds or brazes, but at the various steps or reductions in size to drop a wire from the outside layer *a* (which wire is broken off or tucked into the center when the strands are being laid into rope); and to maintain the evenness of the strands to either reduce the number of the inside wires *b* by one or more, or reduce the diameter of these inside wires. In this way a rope can be reduced by any given size at each step. 55 As an example a rope measures $1\frac{7}{16}$ inches at thickest end is made as shown in Fig. 1 of six strands with 10 outside wires *a* decimal .110 and 4 inside wires *b* each of same size decimal .110 in center of strand. By taking 1 wire from each of both the outside wires *a* and from the 60 inside wires *b* as shown in Fig. 2 the size of rope is reduced to $1\frac{5}{16}$ inches diameter.

Alternatively as shown in Fig. 3 with a rope which measures $1\frac{7}{16}$ inches diameter at thickest end with six strands each having 11 outside wires *a* of decimal .103 70 and seven inside wires *b* of decimal .092, by removing as shown in Fig. 4 one wire from each of the outside strands *a* and reducing the diameter of each of the inside wires *b* to decimal .082 inches, the outside diameter of rope is reduced to $1\frac{1}{2}$ inches. The same process is 75 followed in taking a further wire or more from the outside and a corresponding reduction in the number or in the diameter of the inside or core wires. The center core *c* round which the strands are spun can be made of jute, hemp, manila, and other fibrous material, and 80 of iron or steel or of a combination of any of the above named materials, which is also reduced in size at each step.

Having now described my invention, what I claim as new, and desire to secure by Letters Patent is:— 85

1. A tapering rope having a diminishing number of filaments.
2. A tapering rope having strands composed of a plurality of filaments, diminishing in number throughout its length.
3. A tapering rope having strands composed of a plurality of filaments diminishing in number and a tapering core for said rope.
4. A tapering rope having strands composed of a plurality of filaments diminishing in number and a tapering core for each of said strands.
5. A tapering rope having a tapering core composed of a diminishing number of filaments.
6. A tapering rope having strands composed of a diminishing number of filaments in their outer layer, a tapering core having a diminishing number of filaments for each of said strands, and a tapering core for the rope.

In testimony whereof I have signed my name to this specification, in the presence of two subscribing witnesses.

ALEX. B. ALLAN.
